UNITED STATES PATENT OFFICE.

WILLIAM H. CADWELL, OF CHICAGO, ILLINOIS.

FOLDING COOP.

SPECIFICATION forming part of Letters Patent No. 236,775, dated January 18, 1881.

Application filed December 6, 1880. (No model.)

To all whom it may concern:

Be it known that I, WILLIAM H. CADWELL, of Chicago, in the county of Cook and State of Illinois, have invented certain new and useful 5 Improvements in Folding Coops, of which the following is a specification.

My invention relates to improvements in folding coops designed for the transportation of poultry; and the same consists in the novel 10 construction, arrangement, and combination of the several parts of the coop, by which I am enabled to fold the same, when not in use, into a close, compact form, and to readily erect the same into a strong rigid coop, without the use 15 of any hooks or fastenings, either when erected or folded. The sides of the coop are hinged to the bottom so as to fold inward and lie flat upon the bottom, and the ends also are hinged so as to fold inward and lie flat on top of the 20 folded sides, while the telescoping slat top, which is hinged to the folding ends of the coop, shuts in upon itself and occupies the space on top of the folded sides between the folded ends. When erected, the hinged ends of the 25 coop are held rigid from falling inward by the sides of the coop, which fit inside the same, and from moving outward by the tensile strain of the telescoping top; and the hinged sides are held in an upright position on the outside 30 by a flange or strap attached to the end pieces and on the inside by a shoulder on a cross-piece extending across the telescoping top near its middle, at which point the top may be slightly raised or sprung up to permit the folding 35 and unfolding of the sides.

In the accompanying drawings, which form part of this specification, Figure 1 is a perspective view of a device embodying my invention. Fig. 2 is a like view, showing the same 40 folded. Fig. 3 is a horizontal section on line 3 of Fig. 1, and Fig. 4 is a vertical section on line 4 of Fig. 3.

Similar letters of reference indicate like parts.

In said drawings, A represents the bottom 45 of the coop, of any ordinary construction. The folding sides B are hinged to the rails b, which are attached to the bottom at its side edges, so that the sides B may be folded flat 50 upon the bottom. The folding ends C are hinged at c to the rigid end pieces, c', attached

to the bottom at its ends, which are of such height that when the ends are folded inward they will lie flat upon the folded sides. The inner top edge of the end pieces, c', is beveled off so as to permit the ends to fold, and yet, when erected, to bear or rest upon the pieces c', so that the whole weight will not come upon the pivot of the hinge, which otherwise would be liable to be broken when many coops are 60 piled on top of each other in transporting them. The hinges c² for the folding ends, which I make of ordinary strap-iron, project on the inside slightly over the edge of the end pieces, for the folding sides to open against. 65

The top of the coop is hinged at each end to the ends of the coop, and is composed of slats d and d', arranged alternately to each other, so as to telescope or shut in upon each other when the hinged ends are folded inward. 70

d² are the cross-pieces to which the slats d are secured, and d³ are the cross-pieces to which the slats d' are secured.

d⁴ is a movable slat, secured in place by a pin, d⁵, or other fastening, for the purpose of 75 putting in or taking out the poultry. The rollers or lower cross-pieces, d⁶, of the top are beveled off at their outer lower corner, to permit the folding and secure at the same time a close joint, so that the weight will not rest 80 upon the hinges.

G is a cross-piece, secured to the under sides of the slats d at their ends, thus, together with the cross-piece d², forming a guide and support for the ends of the slats d' to slide in, and 85 the ends of this cross-bar G form shoulders interiorly for the folding sides to fit against and to hold them apart. One of the upright standards g, to which the slats of the folding sides are secured, is placed near the middle, 90 directly opposite the cross-bar G, so that the shoulder has the upright standard for a bearing.

In operation the folding ends are first opened, which at the same time draws out the telescoping top to its full length, and then the folding sides are opened out, the top rising or springing up at its middle enough to allow the sides to pass and drop over the shoulder or end of the cross-bar G. To fold the coop up for transportation the middle of the top is 100 raised so as to allow the sides to be folded, and then the ends are folded down, which at

the same time closes or telescopes the top down flat upon the space between the ends of the folding ends.

Both when folded and erected my improved 5 coop is strong and rigid, so that many coops may be packed on top of each other without injury in transporting them.

What I claim is—

1. In a folding coop, the combination of the 10 bottom with inwardly-folding sides, inwardly-folding ends, and telescoping top hinged to the folding ends, substantially as specified.

2. In combination with the bottom, the folding sides, opening against flanges or projections 15 on the ends of the coop and fitting interiorly

against shoulders or ends of cross-bars attached to the under side of the telescoping top near its middle, folding ends, braced inwardly by the folding sides and outwardly by the tensile strain of the telescoping top, and 20 telescoping top, hinged to the folding ends and adapted to be raised or sprung up near its middle for the purpose of permitting the folding sides to pass the said interior shoulders in folding and unfolding, substantially as 25 specified.

W. H. CADWELL.
